UNITED STATES PATENT OFFICE.

HENRY A. SCHUTT AND CHARLES F. FORDHAM, OF GRAND RAPIDS, MICHIGAN.

CARBURETER.

1,316,545.

Specification of Letters Patent. Patented Sept. 16, 1919.

Application filed May 20, 1918. Serial No. 235,724.

To all whom it may concern:

Be it known that we, HENRY A. SCHUTT and CHARLES F. FORDHAM, citizens of the United States, residing at Grand Rapids, in 5 the county of Kent and State of Michigan, have invented certain new and useful Improvements in Carbureters, of which the following is a specification.

Our invention relates to improvements in 10 appliances for producing an explosive by mixing air with hydrocarbon vapor, and its objects are: first, to provide a means whereby the hydrocarbon, as gasoline, will be reduced to the highest possible degree of 15 vaporization while still in the containing tank; second, to provide a means whereby the amount of hydrocarbon in the containing tank may be held uniform; third, to provide a means whereby the exhaust of gas 20 from the containing tank to the engine may be automatically cut off when the supply of hydrocarbon to the containing tank is exhausted, and, fourth, to provide a means whereby the mixing appliance may be readily removed from, or replaced into the containing tank.

We attain these objects by the mechanism illustrated in the accompanying drawing, in which Figure 1 is a vertical section, 30 partly in perspective, of the containing tank and its several elements. Fig. 2 is a vertical section of the lower end of the tank showing the air passage into the distributing chamber. Fig. 3 is a sectional view of the 35 gas discharge side of the tank practically on the line 3—3 of Fig. 1 showing the valve and ports for regulating the discharge of gas from the tank into the engine cylinder, and, Fig. 4 is a plan of the floor of the tank 40 showing the perforations through which air is made to pass into the distributing chamber and thence through the pipes to the open tank.

Similar numerals indicate similar parts 45 throughout the several views.

This carbureter, or, more properly speaking, this mixer is made up of a container tank, 1, the bottom and end walls of which are made double to form the flues or passageways 8, 9 and 11, and the inner wall of the, relatively, left hand side of the tank passes far enough down in the tank to form a dam or wall at 26 to prevent air from being drawn out through the flue 11 into the gas 55 distributing cylinder 3.

The air distributing mechanism in this

mixer consists of an inverted pan 5, which is placed in the bottom of the tank 1, in such a position that it covers the perforations 10, so that any air that is drawn through the 60 receiving cylinder 2, into and through the flues 8 and 9 will pass through the perforations 10 into the inverted pan 5, and thence through the pipes 6, which open into the pan 5 at 7, and out of these pipes into the 65 main body of gasoline 27. By this means the air entering through the cylinder 2 is made to force the gasoline out of the flues 8 and 9 into the main tank 1, and to pass through gasoline from the openings 10 and 70 75 the pipes 6 and to the surface of the gasoline 27 within the tank.

The pan 5 is set loosely upon the floor, or bottom 20, of the tank, and is arranged to be readily removed by simply lifting it, with 75 the pipes 6, out of the tank.

21 represents an inflow pipe passing from a storage tank into the containing tank 1. The inflow of gasoline through the pipe 21 is governed by an automatically operated 80 valve 22 as follows: An angled lever 25, 25' is pivotally supported in the tank, as at 24, and has a float 23 upon the free end of the lever 25, so set that when the gasoline has raised to a certain height in the tank the float 85 90 will be raised upward until the valve 22 will be so closely set against the inner end of the pipe 21 as to wholly shut off the flow of gasoline, or any other liquid, through the pipe 21 into the tank 1.

The outflow of gas from the tank through the carbureter 4 is governed in like manner. That is, a valve 16 is placed in position, as in the slides 18, to be readily made to move upward and cover the port 19 and 95 prevent gas from passing through said port and out through the port or openings 19'. This action of the valve 16 is brought about automatically, as follows: When the tank is well filled the float 12 is raised sufficiently 100 to move the valve 16 from over the port 19, and when the liquid is well exhausted the weight of the float 12 will be sufficient, acting through the lever 14—15 over the fulcrum rod 13, to force the valve to slide upward over the port 19, and thus shut off the current of gas from the tank into the engine cylinder, through the distributing cylinder 3 into which the ports or openings 19' open.

The cylinders 2 and 3 communicate with the flues 8 and 11 by means of a port 19'

from each cylinder into its respective flue. The holes 17 indicate a convenient means for connecting the ends of the lever 15 with the valve slide 16 by passing the ends of the 5 lever through said holes.

The cover 18 should be so made that it may be readily removed and replaced, as with a boiler cover, &c.

What we claim as new in the art is:

10 1. In a device for mixing air with hydro-carbon vapor, a containing tank having the end walls and the floor made double to form a flue at each end, and at the bottom of the tank, an air receiving cylinder, and a 15 gas distributing cylinder communicating with said end flues, the inner wall of the bottom of the case being perforated for the passage of liquids and air, an inverted pan over the perforations, and air conducting 20 coils connected with the bottom of the pan and opening over the perforations in the floor wall of the tank.

2. In a device for mixing air with hydro-carbon vapor, a containing tank having the 25 end walls and the floor made double to form a flue at each end, and at the bottom of the tank, an air receiving cylinder, and a gas distributing cylinder connected with the tank and communicating with the flues in 30 the end walls, the upper wall of the floor being perforated, an inverted pan resting on the floor over the perforations, tubular coils connected with the pan and opening over the perforations and arranged to open into 35 the liquid contents of the tank below its surface, an inflow pipe, and a valve and float to control the inflow of liquid to the tank.

3. In a device for mixing air with hydro-carbon vapor, a containing tank having 40 the end walls and the floor made double to

form a flue at each end, and at the bottom of the tank, the upper wall of the floor perforated in part, an inverted pan resting on the floor over the perforations and having openings through its upper wall, tubular coils secured in said openings and having upwardly arranged openings at the opposite ends somewhat below the surface of the liquid contents of the tank, an air receiving cylinder connected with the hollow wall on 50 one side of the tank, a gas distributing cylinder connected with the hollow wall on the opposite side of the tank, a liquid inflow pipe, a valve connected with said pipe and controlled by the level of the liquid in the 55 tank, and a valve made to slide upwardly and downwardly by reason of the raising or lowering of the liquid in the tank, the side of the tank back of this valve having an open port for the free flow of vapor into the 60 vapor distributing cylinder.

4. In a device for mixing air with hydro-carbon vapor, a containing tank having the end walls and the floor made double to form a flue at each end, and at the bottom of the 65 tank, the floor having perforations opening from the flue into the tank, means for admitting air into the tank through the flue in the walls and the floor, a removable conductor pan and tubular coils, a pipe for admitting liquid into the tank, means for automatically controlling the flow of liquid through the pipe, a means of escape for gas from the tank, and means for automatically regulating the outflow of gas. 70

Signed at Grand Rapids, Michigan, May 75
8, 1918.

HENRY A. SCHUTT.
CHARLES F. FORDHAM.
